WHEEL TRIM OR SIMILAR ARTICLE

Charles W. Sinclair, Detroit, Mich., assignor to
Kelsey-Hayes Wheel Company, Detroit, Mich.,
a corporation of Delaware

Application April 7, 1952, Serial No. 19,215

Term of patent 14 years

(Cl. D14—30)

To all whom it may concern:

Be it known that I, Charles W. Sinclair, a citizen of the United States of America and a resident of the city of Detroit, in the county of Wayne and State of Michigan, have invented a new, original, and ornamental Design for a Wheel Trim or Similar Article, of which the following is a specification, reference being had therein to the accompanying drawing, forming a part thereof, wherein:

Figure 1 is a side elevational view of my novel design for a wheel trim or similar article;

Figure 2 is a profile view showing the cross sectional contour of the trim of Figure 1;

Figure 3 is a cross section on the line 3—3 of Figure 1;

Figure 4 is a fragmentary side perspective view of the trim.

The dotted lines in Figures 1 and 2 showing a conventional wheel rim and tire are for illustrative purposes only.

I claim:

The ornamental design for a wheel trim or similar article, substantially as shown and described.

CHARLES W. SINCLAIR.
